UNITED STATES PATENT OFFICE

FRANK BERGANDI, OF LOS ANGELES, CALIFORNIA

WIRe BENDING MACHINE

Application filed July 28, 1930. Serial No. 471,139.

The present invention has relation to wire bending machinery and refers more particularly to a machine for forming wire netting for use in mattress springs, fences and other devices employing wire netting.

The general object of my invention is to provide a simple and inexpensive machine capable of forming wire netting at high speed. More particularly my object is the provision 10 of means for forming wire netting in continuous rolls of various widths. These and the further objects and advantages of my invention are hereinafter fully described and illustrated in the appended drawings, of which: 15 Fig. 1 is a front elevation of a machine embodying the invention and with parts broken away for the sake of clearness. Fig. 2 is an end elevation of the device substantially in agreement with Fig. 1 and in this view 20 several parts have also been broken away in order to disclose the interior mechanism. Fig. 3 is a detailed view illustrating the wire forming elements of the structure. Fig. 4 illustrates a detail of the wire feeding mechanism. Fig. 5 shows, on a larger scale, details 25 of the wire cutting mechanism of the device. And Fig. 6 illustrates a modified shape of forming arbor.

On the frame of the machine is mounted a 30 short spindle 1 for continuous rotation by a prime mover, such as an electric motor 2. The inner end of this spindle is slotted to receive a knife shaped arbor 3, which travels in a guide, or chuck 4, and this chuck is firmly 35 clamped in position on the machine frame by means of a suitable cap 5.

Below the arbor, preferably on the floor, 40 is placed a reel 6, on which a spool of wire, 7, is shown deposited. This wire is bent over a series of pulleys, 8, and over a pulley 9, from which the wire is carried to the chuck, 4, the end of the wire having previously been bent into the shape of a hook, 10.

The chuck is made with an internal helical 45 groove, 4^b, in continuation of a notch, 4^a, as best shown in Figure 3. In the first place this hook, 10, is placed over one edge of the arbor and pushed into the notch, 4^a, whereupon the machine is started. The arbor fits the chuck 50 snugly, but the groove, 4^b, affords room

enough for the wire hook, 10, to pass into the chuck and to be carried through the entire helix of the groove. When the opposite edge of the arbor reaches the notch of the chuck, a second bend in the wire has been completed, 55 and this bend is drawn into the notch and through the groove.

In this manner a flattened coil of wire is shot through the machine at high speed. When the desired length of coil is produced 60 the wire is cut close to the arbor as will hereinafter be explained. The coil is now held in a suitable manner, and the machine which has been stopped long enough to hang the coil, is again started and a new coil is formed. 65

The relation of the new coil to the old is such, that the new bend, 10, automatically hooks into the first bend of the old coil, then into the second, and so forth to the end, when the wire again is cut. Behind the machine is 70 mounted a reel, 12. As the netting web grows longer, it is bent over a roller, 13, and fastened to this reel. The latter is constantly being rotated, causing a pull on the web, and this pull is utilized to move the web forward 75 step by step, every time a coil is finished.

Below the roller, 13, is hung a shaft, 14, on which is shown fastened a series of three pointed, star-shaped stops, 15, and a second series of similar stops, 16. All these stops 80 are preferably alike but one series is advanced relative to the other, so that the points of one series of stars are positioned in line with the center of the space between the points of the other series. This relation is best shown in 85 Figure 4. In a suitable manner, as hereinafter will be more fully explained, this shaft is given a one-sixth revolution after the wire coil has been cut, allowing the wire web to be advanced by the pull of the reel, 12, until 90 caught on the points of the star series, 16, which by this time have taken the position formerly held by the series, 15. The web comes to a stop in this position and the machine is again started to wind a new coil. 95

The mechanism shown in the drawings for advancing the web will now be described. Near the bottom of the machine frame is hung a pedal, 25, which by a rod, 26, is connected to oscillate a bell crank, 27, carrying a pawl, 28, 100

for registration with a ratchet wheel, 29, of the shaft, 14. After the machine has been stopped upon completion of a coil this pedal is depressed, causing the pawl to engage the ratchet wheel and to turn the shaft through one-sixth revolution. It is necessary, however, in order to permit the new coil, subsequently to be formed, to wind into the completed coil to shift the shaft, 14, longitudinally one-half the linear pitch of the web. This is readily accomplished by mounting a suitable cam, 30, adjacent the ratchet wheel, 29, and to fasten a projection, 31, on the machine frame to ride in the groove, 32, of this cam, as will readily appear to those versed in the art. The mechanism for cutting the wire each time a new coil is completed is shown to comprise a pair of slides, 35, 36, suitably mounted in guides of the machine frame in a continued alignment and shaped at their opposed ends with V-shaped cutting notches, 37, 38, as best shown in Figure 5. These slides are perforated to receive a pair of levers, 39, 40, which latter are hung on a pivot, 41, positioned directly below the center line of the spindle, 1, and suitably fastened to the machine frame. These levers are connected by means of toggle members, 42, 43, and the latter are, through the medium of a rod, 44, operatively connected with the pedal, 25.

When the pedal is depressed it is seen that the toggle members are drawn downward and the levers, 39, 40, caused to approach each other with the result that the two cutting slides, 35, 36, are drawn together to cut the wire. It is necessary that this cutting operation is completed before the shaft, 14, is rotated to permit the web to advance, and this may readily be accomplished by the proper adjustment of the pawl, 28, to travel idly until the cutting operation is completed.

The mechanism for starting and stopping the machine will now be described. On the pivot, 46, which supports the pedal, 25, is shown mounted a second pedal, 47, which through the medium of a rod, 48, and bell crank, 49, is connected to throw a clutch member, 50, into engagement with a cone 51, of a driven pulley, 52. The latter is, by means of a belt, 53, connected for operation by the motor, 2. The pulley, 52, is mounted on a counter shaft, 54, to which is affixed a pulley or sprocket wheel, 55, connected by a belt or chain, 56, with a pulley or sprocket, 57, of the spindle, 1. In this or any other suitable manner the pedal, 47, is connected to engage the driving clutch to start the machine. On the pedal lever, 47, is mounted a projection, 45, for registration with a pawl, 60, and this pawl is connected for operation by the core, 61, of a solenoid magnet, 63.

When the pedal, 47, is depressed it is to be noted that the projection, 45, becomes engaged by the pawl, 60, to maintain the pedal lever depressed. At the opposite end of the

machine and directly in line with the travel of the oncoming coil is a preferably insulated plate, 64, and this plate is moved by the coil as the latter reaches the end of its travel to close a contact between points, 65, 66, thereby to complete a circuit through a source of electric energy, 67, and the solenoid, 63. The moment this circuit is closed it is seen that the core, 61, is drawn into the magnet, carrying with it a pawl, 60, and releasing the pedal, 47. A suitable spring, 68, is provided normally to maintain the pawl projected.

On the spindle is mounted a brake pulley, 70, on which a brake band, 71, is shown riding, and the latter is, through the medium of a rod, 72, and lever, 73, connected to be released from the drum, 70, when the pedal, 47, is depressed. A suitable powerful spring, 74, is shown employed to set the brake when the solenoid is energized to release the pedal.

It is necessary to provide a suitable slip-joint between the reel, 12, and its driving mechanism in order to compensate for the increasing diameter of the finished roll of netting, and the consequent increasing peripheral speed. This may be accomplished in any suitable, well known manner. In the drawings such slip-joint is indicated by a pair of co-acting friction disks, 20, 21.

The wire used for some purposes is more resilient than other uses require, and some coils may be flatter than others. For these reasons the wire leaving the arbor will, at times, rebound more or less, with the result that the new coil, being formed, is thrown out of line with the finished coil it is required to engage. This condition may be readily overcome by employing an arbor which is more or less twisted forward, in direction of the helix angle, as indicated in Figure 3.

The amount of twist necessary for a given size and quality of wire and shape of coil cannot here be stated, but must be found by actual experience, and arbors to suit should be kept on hand.

The arbor and the chuck are readily removable, and must be changed when a different size or pitch of coil is required. The star shaped stops 15, and 16, must also be adjusted axially, when the linear pitch of the coil is changed. The frame, 22, on which the guide rollers, 8, are mounted, is shown hung on a pivotal stud, 23, and it is free to swing, to adjust itself to the size of the wire coil, 7.

It is well to provide means for maintaining the netting web taut when it is released from the star pointed stops, 15 or 16, and such means is shown to consist in a heavy roller, 75, suspended from the machine frame by means of arms, 76.

Hereinbefore a flattened coil has been referred to. I wish it understood, however, that I may be called upon to produce a helical or some other shape of coil. In Figure 6, for example, is shown an odd shaped arbor,

77. It is important to note that all arbors must be provided with a flat portion, 78, for insertion in the slot of the spindle, 1, and long enough to hold, at least, one complete 5 turn of wire for the purpose of driving the coil through the chuck. The inclined portion, 79, from the flat lip, 78, to the forming arbor proper, should rise gradually in order to afford the wire hook time to slip off lip 10 and to straighten out to the shape of the arbor easily.

The mechanism for rotating the reel, 12, is shown to comprise a disc, 81, driven by a belt, 82, from a pulley (not shown) on the 15 spindle, 1. On the face of the disc is mounted a stud, 83, from which a rod, 84, extends to a lever, 85, carrying a pawl, 86, and this pawl engages a ratchet wheel, 87, of the friction disc, 21. A pawl, 88, is provided to 20 prevent backlash of the ratchet wheel.

The mechanism required for supporting the first coil may be merely a bar, 90, which is pushed through the first coil, whereupon strings or wires, 91, are tied to or hooked into 25 this bar and fastened to the winding reel. Or any other suitable means may be employed.

Because it is difficult, in a machine of this kind, where most of the mechanism is crowded together in a relatively small space, clearly 30 to illustrate the mechanism, many parts and movements are shown out of proportion and true location. But a competent machine designer should be able, from the drawings, in combination with this description, to produce 35 a compact and efficient machine.

I claim:

1. In a wire bending machine, the combination with a driving arbor and a forming chuck, of means for guiding wire to said 40 arbor and chuck, means for supporting each completed coil, a pedal mechanism for cutting off each completed coil and connected to rotate said supporting means to advance the coils and to shift them axially, and a reel 45 yieldingly rotated for accommodation of the finished coils.

2. In a wire bending machine, the combination with a chuck having an internal helical groove and arbor fitted to rotate within said 50 chuck for the purpose of making coils of wire, of a reel yieldingly rotated to receive the finished coils of wire, a shaft having star pointed stops for holding the finished coils in position while a new coil is being wound, and 55 a pedal mechanism for cutting off each finished coil, for partly rotating said shaft to advance the finished coils and for moving the shaft axially one half the linear pitch of the coil in order to position the finished coil.

60 3. In a wire bending machine, the combination with a grooved chuck and an arbor fitted to rotate within said chuck for the purpose of driving wire through the chuck and to form it into a coil, a depressible pedal connected to start the machine to rotate said 65

arbor, a pawl for holding the pedal depressed, a solenoid magnet for withdrawing said pawl from the pedal, and a switch operable by the coil issuing from said chuck to close a circuit through said magnet to withdraw the said 70 pawl.

4. In a wire bending machine, the combination with means for forming coils of wire, of a reel yieldingly rotatable to receive the finished coils, a shaft having star pointed 75 stops for holding the finished coils in position while each new coil is being formed, said stops being axially adjustable to suit the linear pitch of the coils, and means for partly rotating said shaft to advance the finished 80 coils and simultaneously to move the shaft axially one-half the linear pitch of the coils in order to position the last finished coil to receive the coil to be formed.

5. In a wire bending machine, the combination with means for forming and weaving coils of wire, a clutch, a brake, a pedal depressible to operate the clutch to start the machine and simultaneously to release the brake, means to lock the pedal in depressed 90 position, and means actuated by each projected coil to release said locking means.

6. In a wire bending machine, the combination with means for forming and weaving coils of wire, a reel yieldingly rotatable to 95 receive the finished netting, a shaft, a series of star pointed stop members on said shaft, said members being axially adjustable to engage and to hold in position each finished coil while a new coil is being wound, a drum on said 100 shaft, a stationary member riding in a zig-zag peripheral groove of said drum, and means connected to impart step by step rotation to said shaft to advance the finished netting and simultaneously to shift the shaft 105 axially one-half the linear pitch of the coils.

In testimony whereof I have hereunto affixed my signature.

FRANK BERGANDI.
